UNITED STATES PATENT OFFICE.

CHARLES CRAWFORD, OF WEBSTER CITY, IOWA, ASSIGNEE TO CLOSZ & HOWARD MANUFACTURING COMPANY, OF WEBSTER CITY, IOWA, A CORPORATION OF IOWA.

ADJUSTABLE WAGON END-GATE.

1,101,836.

Specification of Letters Patent. Patented June 30, 1914.

Application filed January 31, 1912. Serial No. 674,458.

To all whom it may concern:

Be it known that I, CHARLES CRAWFORD, a citizen of the United States, residing at Webster City, in the county of Hamilton 5 and State of Iowa, have invented certain new and useful Improvements in Adjustable Wagon End-Gates; and I do hereby declare the following to be a full, clear, and exact description of the invention, such as 10 will enable others skilled in the art to which it appertains to make and use the same.

My invention has for its object to provide an adjustable wagon end gate of improved construction, and to such ends, generally 15 stated, the invention consists of the novel devices and combinations of devices herein-after described and defined in the claims.

In the accompanying drawings which illustrate the invention, like characters indicate like parts throughout the several views.

Referring to the drawings, Figure 1 is a rear elevation showing the improved end gate applied to an ordinary wagon box; Fig. 2 is a horizontal section taken on the line x^2-x^2 on Fig. 1; Fig. 3 is a view corresponding to Fig. 1 but showing the end gate raised; Fig. 4 is a view in side elevation showing the rear end portion of a wagon 30 box and the improved end gate applied thereto, the latter being turned down into its open position; Fig. 5 is a section on the line x^5-x^5 on Fig. 1, with the parts in the 35 position shown in Fig. 4; and Fig. 6 is a detail in horizontal section on the same line as Fig. 2, but showing the end gate removed from the wagon box and with some parts broken away.

The numeral 1 indicates the sides, the 40 numeral 2 the bottom of the wagon box. The sides 1 on the inner surface of their rear end portions are shown as provided with vertically extended cleats 2^a and 3 that are spaced apart so that an ordinary end board 45 may be inserted between the same. The outer cleats 2^a only, are useful in the application of my improved end gate. The box bottom 2, at its rear end, is shown as provided with a transverse cleat 4 on its under 50 surface.

The complete detachable end gate comprises an end gate proper and a pair of vertically extended laterally spaced channel-shaped anchoring bars. These channel 55 shaped anchoring bars are detachably and

slidably mounted on the ends of the sides of the wagon box, and, as preferably constructed, each comprises a wooden spacing strip 5, a relatively narrow metal retaining strip 6 and a relatively wide metallic retaining strip 7, which parts are rigidly secured together by short nutted bolts 8^a. The wide retaining strip 7 is provided with a flanged outer edge 7^a. In the application of these anchoring bars to the ends of the sides 60 of the box, they are slid downward with the retaining strips 6 and 7, embracing the outer cleats 2^a of said sides and with a flanged end 7^a of the wide strips 7 overlapping the outer surfaces of the rear ends of 65 the said sides. They are adapted to be securely locked down and in operative position by hooked bolts 8, the threaded upper ends of which work in lugs 9 of small brackets 10 pivoted to the intermediate portions of 70 toggle arms 11. The said toggle arms 11 are pivoted at their lower ends at 12, preferably to reinforcing strips 13 rigidly secured on the lower portions of the wide retaining strips 7. The arms 10 and 11 operate as 75 toggles to draw the hooked lower ends of the bolts 8 tightly against the cleats 4 on the rear end of the box bottom 2. The threaded engagement between the hooked bolts 8 and the brackets 10 permits of adjustment to fit 80 different wagon boxes. When the toggle arms 11 are turned upward, they are adapted to be held against accidental movements by engagement with the notched upper extremities of the latch brackets 14 secured on the 85 intermediate portions of the retaining strips 7.

The end board proper, indicated as an 90 entirety by the numeral 15, is pivoted at its lower end at 16 (see particularly Fig. 5) to 95 the lower portions of the spacing strips 5 of the so-called anchoring bars. A considerable distance from its free end, the end gate 15 is provided with a transverse bar 17, the ends of which project to the outer edges of 100 the anchoring bars. To the ends of the said bar 17, approximately L-shaped and slightly yielding metallic retaining arms 18 are suitably secured. When the end gate 15 is turned upward into its closed position, the 105 projecting ends of the retaining arms 18 embrace the upper rear portions of the sides of the wagon box and assist in holding the same against lateral outward springing movements.

Extending through the projecting ends of the bar 17 and through the secured ends of the retaining arms 18, are quite large perforations 19, through which anchor lugs 20, normally project. The inner ends of these anchor lugs 20 are rigidly secured by nails 21, or otherwise, (see Figs. 2 and 6), to the spacing strips 5 of the so-called anchoring bars. To the projecting ends of the anchor lugs 20, long suspension rods 22 are loosely connected for hinge-like movements in all directions. The free ends of the rods 22 are bent and otherwise provided with stops 23 which will not pass through the perforations 19 of the bar 17. On the outer face of the end gate 15 are hook-like fasteners 24, the purpose of which will presently appear.

As already indicated, the improved end gate, as an entirety, is adapted to be attached to the wagon box by sliding its so-called anchoring bars downward on the cleated end portions of the sides of the wagon box. The manner of rigidly securing these anchoring bars has also been fully noted.

When the end gate 15 is turned upward into its closed position with the ends of the retaining arms embracing the sides of the box, it is adapted to be secured in such position by the rods 22 which are then crossed, as shown in Figs. 1 and 3, and the ends of which, are secured by forcing them under the ends of the fasteners 24. When the end gate 15 is thus locked to the anchoring bars the entire end gate is adapted to be raised, as shown in Fig. 3, so as to permit the discharge of grain by dumping, from the wagon box. All that is necessary in order to move the end gate upward, as shown in Fig. 3, is first to release the hook rods 8 and then to slide the retaining bars vertically upward on the cleated ends of the wagon box sides.

When corn, or the like, is to be shoveled from the rear end of the box, the end gate 15 is adapted to be turned downward, as shown in Figs. 4 and 5. To do this, it is only necessary to disconnect the suspension rods 22 from the fasteners 24, and when the said rods are thus released, they will pass through the perforations 19 of the bar 17

and permit the end gate 15 to turn down into the position shown in Fig. 4, where the stops 23 on the ends of the said rods 55 engage the ends of retaining arms 18 on the bar 17 and support said end gate in the down-turned position indicated.

The improved end gate described is strong and durable, may be easily applied to a wagon box of standard or ordinary construction, and furthermore, is extremely convenient and efficient for use in handling of corn and various similar articles.

What I claim is:

1. An end gate for wagon boxes comprising anchoring bars having interlocking vertical sliding engagement with the ends of the sides of said box, means for locking said anchoring bars to the wagon box, said means comprising toggle arms pivotally secured to said anchoring bars, lug-equipped brackets pivotally secured to the intermediate portions of said toggle arms, hook bolts having screw threaded engagement with the lugs of said brackets and adapted to engage the wagon box, means for locking said toggle arms to said anchoring bars, when in normal positions, and an end gate pivoted at its lower end to the lower portions of said anchoring bars.

2. An end gate for wagon boxes, comprising anchoring bars having interlocking vertical sliding engagement with the ends of the sides of said box, means for locking said anchoring bars to the wagon box, said means comprising toggle arms pivotally secured to said anchoring bars, lug-equipped brackets pivotally secured to the intermediate portions of said toggle arms, hook bolts having screw threaded engagement with the lugs of said brackets and adapted to engage the wagon box, latch brackets on said anchoring bars with which said toggle arms interlock with a spring action when in operative positions, and an end gate pivoted at its lower end to the lower portions of said anchoring bars.

In testimony whereof I affix my signature in presence of two witnesses.

CHARLES CRAWFORD.
